GEARLESS OSCILLATING DRIVE

Howard S. Bancroft, Sharon, Pa.

Application January 22, 1947, Serial No. 723,512

3 Claims. (Cl. 74—47)

1

This invention relates to drive mechanisms and more particularly to drive mechanisms adapted for use in washing machine constructions.

The principal object of the invention is the provision of a drive mechanism for transposing rotating movement as from a drive shaft to oscillating movement on a driven shaft.

A further object of the invention is the provision of a gearless oscillating drive mechanism of extremely simple and durable construction capable of economic manufacture.

A still further object of the invention is the provision of a gearless oscillating drive mechanism including mechanical means for transporting rotating motion from a drive shaft to oscillating motion in a driven shaft positioned at right angles to the said drive shaft.

A still further object of the invention is the provision of a gearless oscillating drive in which a minimum of moving parts are employed and the mechanism resulting is therefore capable of substantial duty over long life.

The gearless oscillating drive shown and described herein is particularly adaptable for use in washing machine constructions wherein rotating movement of a drive shaft such as motivated by an ordinary electric motor is of necessity transferred to oscillating motion on a vertical shaft which in turn is used to impart oscillating movement to an agitator such as used in washing machine constructions.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation with parts broken away and parts in cross section illustrating the adaption of the gearless oscillating drive to a washing machine construction.

Figure 2 is a vertical cross section of the gearless oscillating drive with parts broken away.

Figure 3 is a side elevation of the gearless oscillating drive shown in Figure 2 and taken on line 3—3 thereof.

Figure 4 is a side elevation of the gearless oscillating drive with parts in cross section and taken on line 4—4 of Figure 2.

2

Figure 5 is a horizontal cross section taken on line 5—5 of Figure 2.

Figure 6 is a horizontal cross section similar to Figure 5 and showing a modified form of the gearless oscillating drive.

Figure 7 is a vertical cross section taken on line 7—7 of Figure 6 and further illustrates the modification of the gearless oscillating drive.

Figure 8 is a horizontal cross section of a modified form of gearless oscillating drive.

Figure 9 is a vertical section taken on line 9—9 of Figure 8.

By referring to the drawings and Figure 1 in particular it will be seen that a washing machine construction is disclosed which includes a tub 10 having an agitator 11 positioned therein on a supporting tubular member 12, the lower portion of which extends through an opening 13 in the bottom of the tub 10 and about which opening 13 suitable glands 14 are positioned to form a water-tight connection. The tub 10 is supported in elevated relation to a supporting surface such as a floor by means of a plurality of legs 15. A shelf 16 is positioned between the legs 15 and serves to support an electric motor 17.

The agitator 11 in the tub 10 of the washing machine is adapted to be moved in an oscillating movement as is customary in washing machines of this general type. In order that such movement may be imparted thereto, a vertical driven shaft 18 is positioned in the tubular member 12 and the uppermost end of the vertical driven shaft 18 extends out of the uppermost end of the tubular member 12 and terminates in a squared end section 19. The squared end section 19 is adapted to register with a similarly squared socket in the apex of the agitator 11. A gland 20 is positioned about the vertical driven shaft 18 so as to close the uppermost end of the tubular member and prevent water from the tub 10 of the washing machine from entering the same.

The construction thus far described approximates the ordinary washing machine construction in which an oscillating agitator is used.

In order that the vertical driven shaft 18 may be coupled to the electric motor 17 so that oscillating movement may be imparted to the vertical driven shaft 18, a gearless oscillating drive has been positioned in operative relation to a drive shaft 21 of the electric motor 17 and the lower portion of the vertical driven shaft 18. The gearless oscillating drive comprises the coupling and means for translating the rotating movement

of the horizontal drive shaft 21 to oscillating movement in the vertical driven shaft 18.

The gearless oscillating drive is shown in enlarged detail in Figures 2, 3, 4 and 5 of the drawings and by referring now to Figure 2, in which a vertical cross section of the mechanism is illustrated, it will be seen that the vertical driven shaft 18 has a slot 22 formed therein in which a block 23 is positioned for vertical movement. A stud 24 is threaded into a drilled and tapped opening and has a projecting section having a ball 25 thereon. It will be observed that the projecting section carrying the ball 25 extends outwardly through the slot 22 and through a registering opening 26 in the tubular member 12. Positioned on the side of the tubular member 12 and forming an enclosure about the opening 26 therein there is a casing 27 which positions a disc 28 which in turn is formed on one end of the drive shaft 21 heretofore referred to as being in connection with the electric motor 17. A bushing 29 is bolted or otherwise affixed to the casing 27 and serves to position the drive shaft 21 in a suitable bearing and at the same time hold the disc 28 in operative relation to the casing 27 for relatively free rotation therein.

In order that the motion of the disc 28 may be imparted to the vertical driven shaft 18, an opening 30 is formed in the disc 28 and in the face thereof in registry with the opening 26 in the tubular member 12 so that the ball 25 on the projecting section of the stud 24 will register therein. In order that abnormal wear will not take place, a bushing 31 is positioned in the opening 30 for direct frictional engagement with the ball 25. It will thus be seen that at such time as the drive shaft 21 is rotated as by the electric motor 17, the disc 28 will revolve and the opening 30 therein will define a circle which will impart the same movement to the stud 24 by reason of the ball 25 thereof being in registry in the opening 30. As the disc 28 revolves, the ball 25 on the projecting section of the stud 24 will follow the circular movement of the opening 30 in the disc 28 and move in and out of the opening 30 in accordance with the access of the vertical driven shaft 18 which controls the positioning of the stud 24. Thus, it will be seen that the ball 25 on the projecting section of the stud 24 will be deeply seated in the opening 30 in the disc 28 when the opening is at the uppermost end lowermost positions, respectively, of its circular travel and that the ball 25 on the projecting section of the stud 24 will move slightly out of the opening 30 at such times as the opening 30 is at the respective side positions of the circular movement. This side-to-side movement of the ball 25 on the projecting section of the stud 24 imparts desirable oscillating movement to the vertical driven shaft 18 and hence to the agitator 11 which is operatively connected with the uppermost end thereof as heretofore described. Thus, the agitator 11 in the tub 10 of the washing machine is caused to oscillate.

The vertical movement of the ball 25 on the projecting section of the stud 24 is compensated for by the vertical travel of the block 23 in the slot 22 of the vertical driven shaft 18 as heretofore described so that such vertical movement is not imparted to the vertical driven shaft 18. The vertical movement being dissipated, the sole movement of the gearless oscillating drive is the oscillating movement imparted to the vertical driven shaft 18.

In Figure 3 of the drawings a detailed view of

the mounting of the bushing 29 may be seen and it will be observed that the flanged bushing 29 is affixed as by bolts 32 to the casing 27.

In Figure 4 of the drawings a vertical cross section of the gearless oscillating drive is shown and it will be observed that the disc 28 is shown cut away with the opening 30 therein exposed and the ball 25 on the projecting section of the stud 24 may be seen in position therein. In Figure 4 the vertical cross section illustrates the vertical movement of the block 23 in the tubular member 12, which action dissipates the vertical motion and the same is not therefore imparted to the vertical driven shaft 18.

In Figure 5 of the drawings a horizontal cross section taken on line 5-5 of Figure 2 may be seen. It will be observed that the ball 25 on the projecting end of the stud 24 is in uppermost position, as shown in Figures 2, 3 and 4, and the movement imparted thereby to the vertical driven shaft 18 is indicated by arrows in the figure. It will thus be seen that the block 23 is capable of vertical travel by reason of its positioning in the oppositely disposed slots 22 in the vertical driven shaft 18.

In Figures 6 and 7 of the drawings, modifications in the structure hereinbefore disclosed and described may be seen, the modifications comprising a mechanical device approximating the utility of the vertically sliding block 23 in the device heretofore described. In Figures 6 and 7 a vertical driven shaft 33 is positioned for rotating movement in a tubular member 34 and has a cut away area 35 in which a section 36 is pivoted as by a pivot 37 positioned transversely of the section 36 and the vertical driven shaft 33. A stud 38 having a ball 39 on a projecting end thereof is adapted to register in a socket 40 formed in a rotatable disc 41 which in turn is positioned on one end of a drive shaft 42. It will thus be seen that rotating movement imparted to the disc 41 will cause the ball 39 to travel in a circular pattern which will impart oscillating movement to the vertical driven shaft 33 and that the vertical movement will be dissipated by the vertical hinge action of the pivoted section 36 in which the stud 38 carrying the ball 39 is positioned. Thus desirable oscillating movement may be imparted to the vertical driven shaft 33 and objectionable vertical movement thereof eliminated.

A still further modification of the invention may be seen by referring to Figures 8 and 9 of the drawings wherein a modified structure capable of providing oscillating movement of a shaft through a complete half revolution is disclosed. In Figures 8 and 9 of the drawings a driven shaft 43 is positioned in a bushing 44 which in turn is affixed to a casing 45. A rotatable disc 46 is formed on one end of the drive shaft 43 and is located within the casing 45. A portion of the rotatable disc 46 is cut away to provide an area 47 in which an arm 48 may be positioned. The arm 48 is pivoted to the disc 46 by a pivot 49 and the opposite end of the arm 48 is provided with a socket 50 and a retaining nut 51. When this structure is used in connection with a driven shaft 52 positioned in a tubular guide member 53 and having a block 54 positioned in oppositely disposed slots 55 therein (as disclosed in Figures 2, 3 and 4 of the drawings and heretofore described), and the block 54 is provided with a stud 56 having a ball 57 formed on a projecting end thereof, it will be seen that the rotating movement of the disc 46 will be transmitted to the

driven shaft 52 through the pivot 49, the arm 48 and the ball 57 engaging the socket 50 in the arm 48.

As the ball 57 is formed on the projecting end of the stud 56 which in turn is positioned in the block 54, the oscillating movement imparted to the driven shaft 52 may be of different degree than that of the mechanism heretofore described in that the arm 48 will swing out of its position in the disc 46 so as to move the stud 56 and the ball 57 thereon through a complete half circle and thereby impart that degree of motion to the driven shaft 52. The hinging action of the arm 48 on the pivot 49 makes possible the large degree of oscillating movement obtained and the block 54 sliding vertically in the slots 55 in the driven shaft 52 enable the vertical movement to be dissipated.

It will thus be seen that three forms of the gearless oscillating drive have been disclosed, all of which are of extremely simple construction, capable of economic manufacture and efficient in operation.

Having thus described my invention, what I claim is:

1. An oscillating drive mechanism including a drive shaft and a driven shaft, a block positioned for axial movement in the said driven shaft and a stud positioned in the said block and having a ball formed on a projecting end thereof, and means on the drive shaft for engaging the said ball so that circular movement may be imparted thereto.

2. An oscillating drive including a driven shaft and a drive shaft, means for rotating the drive shaft, a disc formed on the drive shaft and a socket positioned in said disc, a slot formed in the

said driven shaft and a block positioned therein for axial movement thereof, and means connecting the said block with the said socket in the disc so that rotating movement of the disc may be transposed to oscillating movement in the drive shaft thereby.

3. Means for oscillating an agitator of a washing machine construction, the said means including a tubular guide member, a driven shaft positioned in the said tubular guide member, an opening formed in the said guide member and a casing positioned thereabout, a rotatable member positioned in the said casing and a socket formed in the said rotatable member, a slot formed in the said driven shaft and a block positioned therein for axial travel thereof, a stud having a ball formed on a projecting portion thereof positioned in said block, the said ball engaging the said socket in the said rotatable member, and means for imparting rotating movement to the said rotatable member.

HOWARD S. BANCROFT.
